UNITED STATES PATENT OFFICE.

JAKOB SKANDORA, OF RACINE, WISCONSIN.

STOP MEANS.

1,300,232.

Specification of Letters Patent. Patented Apr. 8, 1919.

Application filed September 2, 1916. Serial No. 118,265.

To all whom it may concern:

Be it known that I, JAKOB SKANDORA, a subject of the King of Hungary, residing at Racine, in the county of Racine and State of Wisconsin, have invented certain new and useful Improvements in Stop Means, of which the following is a specification.

The primary object of the invention is the provision of an improved stop means for spring motor operated fans adapted for releasably holding the motor shaft against rotation at will.

With this general object in view and others that will appear as the nature of the invention is better understood, the same consists in the novel construction, combination and arrangement of parts hereinafter more fully described, illustrated in the accompanying drawing and claimed.

20 In the drawing forming a part of this application and in which like designating characters refer to corresponding parts throughout the several views:—

Figure 1 is a sectional fragmentary view 25 of a fan casing and its spring motor,

Fig. 2 is an elevational fragmentary view of the winding mechanism and stop means for the motor, partly illustrated by dotted lines, and

30 Fig. 3 is a vertical detail sectional view illustrating a portion of the stop means.

It will be understood that the present stop means may be adapted for any form of fan construction, the same being herein illustrated in connection with a casing 10 having a power shaft 18 in the lower portion thereof. A flat coil spring 19 constituting the spring motor of the device has one end thereof secured to the shaft 18 while its other end is anchored to a post 20 within said casing. A toothed stop wheel 21 is mounted upon the shaft 18, and a latch bolt 22 is arranged therebeneath and provided with a spring 23 adapted to normally maintain the reduced upper end 24 of the bolt engaged with the teeth of the wheel 21, thus preventing rotation of the shaft 18. An angular arm 27 having a handle or knob 25

projects from the lower end of the bolt 22 and extends through an angular side slot 26 in the casing 10, said arm or angular end portion 27 being adapted for reception within the lateral extension 28 of the slot 26 for retaining the bolt 22 lowered with the spring 23 under compression when the bolt is out of engagement with the stop wheel. The lateral movement of bolt 22 is allowed by reason of the fact that the apertures 28 in the superposed guide brackets 29 therefore are of greater diameter than said bolt.

A winding handle 33 is carried by one end of the shaft 18 outwardly of the casing whereby the spring 19 may be placed under tension when the latch bolt 22 is released, the spring being maintained in its set coiled position when the latch bolt is in engagement with the stop wheel 21. Upon operating the arm 27 for releasing the stop bolt, the spring 19 is allowed to unwind for operatively turning the shaft 18.

An inexpensive stop means for spring motor operated fans is thus provided in which the motor is readily rewound and the operation thereof conveniently controlled.

What I claim as new is:—

A stop means comprising a support having a vertical wall, a horizontal revoluble shaft carried by said support, a toothed stop wheel secured on said shaft, a pair of spaced superposed brackets rigid with said vertical wall of the support beneath said shaft and having aligned apertures therethrough, said support having an angular slot in said vertical wall thereof, a latch bolt of a diameter smaller than that of the bracket apertures 80 loosely slidably arranged in the latter, and a spring to project said bolt upwardly into engagement with the teeth of said stop wheel, said bolt having an angular end extending through said angular slot adapted 85 to be moved laterally in the latter whereby the bolt is maintained out of engagement with said stop wheel, substantially as described.

In testimony whereof I affix my signature. 95
JAKOB SKANDORA.
